WEFT BOBBIN FOR AUTOMATIC WEFT SUPPLY

Eduard Egli and Edwin Schoch, Ruti, Switzerland, assignors to Maschinenfabrik Ruti vorne Caspar Homberger, Ruti, Switzerland

Application November 22, 1934, Serial No. 754,364
In Switzerland November 29, 1933

1 Claim. (Cl. 139—207)

In known weft carriers (Northrop pirns) for looms with automatic change of bobbin, the hold-fast member, provided with rings or beads, is round in shape. This shape has the disadvantage that the fresh bobbin to be inserted is liable to slip off upon the bobbin located in the shuttle, thereby injuring the inner edges of the shuttle frame. It also has the disadvantage that the bobbin rotates, and a definite angular position in the shuttle cannot be attained. To attain this definite position, as is required in the case of bobbins with a feeler slot, and in the case of flat bobbins, various expedients are adopted, such for example as providing guiding holes in the hold-fast member of the bobbin, in which guiding pins on the weft hammer engage, and also milling off the outermost hold-fast part of the bobbin, and in conjunction therewith providing introducing or holding jaws in the shuttle. With all these expedients, however, it is not possible to attain the requisite position of the bobbin in the shuttle satisfactorily and without disturbance, for either the bobbin is rotated, or else it is only possible to constrain the bobbin to take up the correct position with a great expenditure of force.

Now the present invention relates to a weft carrier (Northrop pirn) for automatic weft supply, wherein the attaining of a definite angular position of the carrier in the shuttle is possible without resorting to special expedients, and the tendency of the bobbin that is to be inserted to slip off upon the bobbin in the shuttle is counteracted. This weft carrier is distinguished by the fact that the hold-fast member provided with holding beads for the prevention of twisting and slipping of the fresh weft bobbin to be inserted, upon the weft bobbin still located in the shuttle, is made exactly or approximately elliptical in cross section. The narrow sides of the hold-fast member of substantially elliptical cross section are preferably flattened.

One constructional example of the invention is illustrated in the accompanying drawing, in which

Figure 1 is a plan,

Figure 2 an elevation, and

Figure 3 a view from the left-hand end.

Figure 4 is a cross section through the shuttle and the hold-fast member of the bobbin, and

Figure 5 illustrates the position of the weft carriers, when the bobbin to be automatically inserted strikes with the flattened narrow side upon the bobbin in the shuttle.

In the drawing, 1 denotes a weft carrier or

pirn, for instance for looms with automatic change of bobbin, here shown as a flat bobbin with a conical rear portion 2, and with two opposite feeler slots 3. The hold-fast member or spool butt 4 is exactly or approximately elliptical in shape, and has at the lower end two lateral flattenings 5, which ensure a definite position in the bobbin magazine. The radius of curvature of the two opposite broad sides 6 is greater than half the distance between these two sides. The two opposite narrow sides 7 of the substantially elliptical cross section of the hold-fast member 4 are flattened. The hold-fast end 4 is provided with holding beads 8, which engage in recesses in a hold-fast spring 9 of the shuttle 10, shown in Figure 4.

Owing to the shape of the hold-fast member of the bobbin in the manner described, the result is obtained that the latter is inserted in the correct position in the shuttle without further trouble, that is to say, for example, with the feeler slot 3 in front, or, in the case of flat bobbins, with the broad side of the cop at the top. Owing to the flattened narrow sides 7 of the hold-fast member 4, the further result is obtained that in the case of automatic weft supply the fresh bobbin 11 (Figure 5) to be inserted does not tend to slip down upon the bobbin 12 located in the shuttle in the transverse direction, and to rotate about its own axis, which latter tendency would occur in the case of ordinary bobbins with a round hold-fast member.

The beads 8 may consist of individual parts. In this case the latter are themselves of the shape described, as regards the hold-fast member 35 of the bobbin.

The bobbin may consist of wood, metal, artificial resin, or any other suitable material.

What we claim is:

A weft carrier for looms with automatic change of bobbins, comprising a flat front portion with the long axis in the horizontal direction, to carry the weft, a conical rear portion having two opposite feeler slots, a solid hold-fast member provided with holding beads and elliptical in cross section for the purpose of preventing rotation and slipping of the fresh bobbin of weft to be inserted upon the weft bobbin still located in the shuttle, the narrow sides of the solid hold-fast member being flattened and the long axis of the elliptical cross-section of the hold fast member being perpendicular to the long axis of the flat cross-section of the weft-carrying portion of the weft carrier.
